UNITED STATES PATENT OFFICE

PAUL E. WEBB AND FRANK A. WEBB, OF ARKANSAS CITY, KANSAS

PROCESS OF MAKING FUEL MIXTURES

No Drawing.

Application filed May 7, 1928. Serial No. 275,828.

This invention relates to a method of producing a fuel mixture, and is more particularly directed to the fuel employed in connection with oil burners, described and 5 claimed in our co-pending application, Serial #257,765, filed Feb. 28, 1928.

Acetylene gas is formed usually by the action of water on calcium carbide which at best is a rather expensive method for the 10 preparation of the gas for commercial purposes. Where it is possible to utilize a cheap hydrocarbon for the saturation of the acetylene gas with a sufficient quantity of the hydrocarbon vapors to not only maintain combustion but to provide a complement of 15 B. t. u.'s, a fuel is obtained which may be consumed at a cost considerably below the cost of the dry acetylene gas.

An object of the present invention is the 20 provision of a fuel formed of acetylene gas and one of the saturated hydro-carbons which have been so blended that when burned a flame will be produced which will not give off any carbon monoxide.

Another object of the invention is the provision of a process for producing a fuel for combining a hydro-carbon of the acetylene series with one of the unsaturated hydro-carbons, preferably a lower member of the series, 25 whereby a fuel is produced having predetermined proportions of the two elements so incorporated that the composition will act in all respects as if it were formed of a simple compound and will sustain combustion without the production of carbon monoxide, and at a cost considerably below that of the dry 30 gas of the acetylene series.

This invention will be best understood from a consideration of the following detailed description; nevertheless, it is to be understood 40 that the invention is not confined to the disclosure being susceptible of such changes and modifications as shall define no material departure from the salient features of the invention as expressed in the appended claims.

In carrying out our invention a chamber of any suitable dimensions is employed which contains a predetermined quantity of one of the lower members of the homologous series 45 of the unsaturated hydrocarbons, preferably

pentane, expressed by the empirical formula as C_5H_{12} . Pentane is found in nature in enormous quantities, as petroleum or mineral naphtha, and is also found in nature with other paraffins. It is normally a colorless liquid, boiling at 37° C. which is insoluble in 55 water, but soluble in alcohol, ether and other organic liquids, and when acetylene gas is passed through pentane, said gas will become saturated with the hydrocarbon.

The simplest member of the acetylene series which is in the form of a gas such as acetylene, having the empirical formula C_2H_2 , is passed through the liquid pentane whereby a predetermined quantity of the pentane will be taken up by the gas which acts as a vehicle. At the time of the passing of the acetylene 60 gas through the pentane it is probable that no chemical effect takes place, but a physical relation exists between the acetylene gas and the vapors of the pentane so that when the new fuel composed of the gas and pentane vapors in the proper proportions, is ignited, a complete combustion will take place.

Due to the fact that the acetylene gas has a tendency to absorb too great a quantity of the pentane, for an efficient combustion of the mixture of the acetylene gas and pentane, a predetermined quantity of dry acetylene is mixed directly with the pentane-saturated 75 acetylene gas while being supplied to the burners for definitely controlling the proportions of the mixture necessary for complete combustion of the product.

It is computed that two hundred (200) pounds of calcium carbide contains approximately one million three hundred and fifty thousand (1,350,000) B. t. u.'s, while one (1) gallon of pentane contains one hundred and ten thousand (110,000) B. t. u.'s. By employing approximately forty-nine (49%) per cent of the two hundred (200) pounds of calcium carbide in connection with fifty-one (51%) per cent of pentane which amounts to approximately six and four tenths (6.4) gallons, it is found that one million three hundred and fifty thousand (1,350,000) B. 80 t. u.'s, are obtained. In other words ninety-eight (98) pounds of calcium carbide contains six hundred sixty-one thousand and five 85

50

hundred (661,500) B. t. u.'s, while the six and four-tenths (6.4) gallons of pentane contain six hundred eighty-eight thousand and five hundred (688,500) B. t. u.'s, thereby totalling one million three hundred and fifty thousand (1,350,000) B. t. u.'s or the number of the B. t. u.'s contained in two hundred (200) pounds of calcium carbide. As an economical fuel it will be found that by the use of the 10 acetylene gas in connection with pentane in the proper quantities which contain together the one million three hundred and fifty thousand (1,350,000) B. t. u.'s, a great saving is had, due to the fact that the cost of the pentane and the calcium carbide which is necessary to be employed with a predetermined quantity of pentane is approximately one half of the cost of two hundred (200) pounds of calcium carbide, which is the equivalent in 15 B. t. u.'s to the ninety-eight (98) pounds of calcium carbide and the six and four tenths (6.4) gallons of pentane.

While pentane has been particularly stated as the liquid hydrocarbon to be employed, 20 other hydrocarbons of the same series may be mixed with the pentane in various proportions which will obtain approximately the same results. Therefore, it is possible to have a mixture of various hydrocarbons of 25 the same series of the general formula C_nH_{2n+2} such as the following:— C_4H_{10} , C_5H_{12} , C_6H_{14} . These hydrocarbons may be mixed in equal quantities and usually contain approximately three (3%) per cent of the hydrocarbon designed by C_7H_{16} and C_8H_{18} . The 30 hydrocarbon of the paraffin series normally contains about ninety-seven (97%) per cent pentane and three (3%) per cent of certain other of the hydrocarbons of the paraffin 35 series.

40 The wet acetylene gas when properly proportioned gives a very efficient fuel for use in a welding torch when employed under fifteen (15) pounds pressure or less.

45 We claim:—

1. A method of producing fuel which comprises passing acetylene gas through pentane, whereby the acetylene gas will act as a vehicle for carrying predetermined quantities of the 50 pentane and then modifying the mixture of the acetylene gas and pentane with pure acetylene gas.

2. A method of manufacturing a fuel which comprises passing acetylene gas through a 55 liquid hydrocarbon of the paraffin series and then thoroughly mixing a predetermined quantity of dry acetylene gas with the mixture formed by passing the acetylene gas through the liquid hydrocarbon.

60 Signed at Arkansas City in the county of Cowley, and State of Kansas this 1st day of May, A. D. 1928.

PAUL E. WEBB.
